UNITED STATES PATENT OFFICE

165,367

PERAMBULATOR

Henry B. Eging, Shaker Heights, Ohio

Application July 20, 1951, Serial No. 15,973

Term of patent 14 years

(Cl. D14—14)

To all whom it may concern:

Be it known that I, Henry B. Eging, a citizen of the United States, residing at Shaker Heights, in the county of Cuyahoga and State of Ohio, have invented a new, original, and ornamental Design for a Perambulator, of which the following is a specification reference being had to the accompanying drawing, forming a part thereof.

Figure 1 is a perspective view of a perambulator in operative position, showing my new design;

Figure 2 is a front view thereof;

Figure 3 is a side view thereof; and

Figure 4 is a plan view thereof.

I claim:

The ornamental design for a perambulator, as shown.

HENRY B. EGING.
